UNITED STATES PATENT OFFICE.

LEVI STEVENS, OF WASHINGTON, DISTRICT OF COLUMBIA.

IMPROVEMENT IN THE MANUFACTURE OF ILLUMINATING-GAS.

Specification forming part of Letters Patent No. **87,123**, dated February 23, 1869.

To all whom it may concern:

Be it known that I, LEVI STEVENS, of Washington city, in the District of Columbia, have invented certain new and useful Improvements in Apparatus for Distilling Coal and Mixing and Retorting Vapors in the Manufacture of Illuminating-Gas; and I do hereby declare the following to be a full, clear, and exact description of the same, reference being had to the accompanying drawings, making a part of this specification, in which—

Figure 1 represents, in perspective, so much of the apparatus as will illustrate my invention; and Fig. 2 represents a vertical longitudinal section through the same.

Similar letters of reference, where they occur in the separate figures, denote like parts in both of them.

In the manufacture of illuminating-gas from coal, as now practiced, the first of the process is expended in the distillation of coal-tar, which is not only useless, but is also a great waste of gas-making material. Besides, this coal-tar clogs up the retorts. So, too, in recharging a retort, the chill produced by the charging in the cold material results in the production of coal-tar, and not in gas, and this production of this worse than useless material will continue until the degree of heat required to eliminate gas is again restored to the retort or chamber containing the gas-making material.

It is impracticable to stop the production of coal-tar at the outset of the process, or when the retorts become chilled by charging in the cold material, if the generating of the vapors and the retorting be attempted in one and the same retort or chamber.

My invention consists in combining with the two retorts or chambers, and with their fire-space or radiated heat, a coil of pipe for containing steam, and in which the steam is dried or superheated, and thence passed into the coal-distilling chamber of the pair, to commingle with the vapors therein, and thence go to the other chamber to be retorted or converted into a fixed gas.

To enable others skilled in the art to make

and use my invention, I will proceed to describe the same in connection with the drawings.

A represents a bench, in which two sets of retorts, B and B', are arranged. A single set may be so arranged, or any other number of sets more than two.

Underneath the retort B, in which the gas-making material is charged, is placed the fire chamber or box C, with suitable grate-bars, fire and smoke flues, ash-box, and fuel-feeding and draft openings; and above the retort B, with fire-space D intervening, is placed the upper or gas-making or converting retort or chamber B'. A passage, a, unites the chambers of the lower and upper retorts.

Steam, from any suitable generator, is passed through a coil or series of pipes, b, arranged for convenience and economy between the arches c c' of the bench, where it is dried or superheated, and from thence is taken through the pipes d e into the distilling-chamber B, and passed over and mixed with the vapor arising from the distillation of the coal therein, and these mixed vapors pass through the communicating passage a into the upper chamber, B', where they are retorted and converted into a fixed gas.

The openings f through the walls of the fire-chamber are for allowing the heat and flame to surround the retorts.

In this process the hydro-oxygen oxidizes the carbon and leaves free hydrogen, and prevents the carbon from depositing in the retorts or the formation of coal-tar, which is a clear loss of material, and, moreover, fills or clogs the retorts.

The two retorts or chambers are separated by supports that leave fire space or passages between them, and when the lower chamber is being charged with fresh gas-making material, the chill does not extend to the retorting or converting chamber, which continues its high temperature, so that no coal-tar is distilled or deposited in them.

The great advantage of this process of distilling in one retort and converting and fixing the gas in another retort is in the immense

saving of the gas-making material and the largely-increased product of gas from a given quantity of coal.

Having thus fully described my invention, what I claim therein as new, and desire to secure by Letters Patent, is—

In combination with the double retorts or chambers, as herein represented, the series of steam-pipes for superheating and carrying the

superheated steam into the retort or chamber containing the coal or other gas-making material, mixing the vapors therein, and retorting them in the other chamber or retort, substantially as and for the purpose set forth.

LEVI STEVENS.
